SHATTERPROOF VALVE TYPE LIGHTNING
ARRESTER.

Norman K. Osmundsen, Bloomington, and John P. Cage, Richland Township, Monroe County, Ind., assignors to Westinghouse Electric Corporation, Pittsburgh, Pa., a corporation of Pennsylvania

Filed Feb. 26, 1963, Ser. No. 261,134
3 Claims. (Cl. 315—36)

The present invention relates to valve type lightning arresters and more particularly to valve type lightning arresters which are provided with shatter prevention structure.

When a lightning surge current is discharged through a valve type arrester, a system follow current will also tend to flow through the arrester until its normal voltage insulative character is recovered. Under normal conditions, the follow current is thus interrupted without damage to the arrester device. However, occasionally the lightning or follow energy flowing into the arrester causes block or gap damage such that follow current continues to flow through the low impedance gap or gaps with nominally little impedance limitation from the block itself. In this fault condition, heat from and arcing of the follow current can have explosive or shattering effects on the arrester device. The extent to which these effects occur is dependent in some measure upon the energy capacity of the system in which the arrester is connected and further upon the impedance limitations within the system itself against ground current flow through the arrester under faulted arrester condition.

More particularly, shattering or explosion of the arrester device apparently is caused by the build up of gas pressure due to the faulty block or faulty gap structure or by arcing along or against the inside of the arrester housing or by a combination of these factors. Even if a drop-out assembly or mechanism is used in the arrester to provide follow current interruption after a block fault occurs, the possibility of a shatter or explosion still exists. Thus, damage can occur in some instances before drop-out occurs and in other instances even after drop-out occurs if drop-out does not release pressure or after current interruption if sufficient pressure is in the interim built up in the arrester and the arrester is later jarred or impacted by a serviceman or by other means.

In accordance with the broad principles of the present invention, a valve type lightning arrester having an outer housing of insulative material such as porcelain comprises an electrically insulative and heat resistant inorganic flexible or molded liner member disposed between internally positioned series gap and block assemblies and the housing. The liner can be disposed between either the gap assembly or the block assembly and the housing or between the entire series combination of assemblies and the housing. In this manner, the gap and block assemblies or either of these can be spaced from the housing by the liner, and the arrester is substantially prevented from shattering or exploding when a fault develops in the arrester block assembly. Evidently, explosion prevention is due to factors including gas absorption and arc inhibiting action by the liner.

Accordingly, it is an object of the invention to provide a novel and efficient valve type arrester which is protected from shatter or explosion following the development of a fault in the arrester.

Another object of the invention is to provide a novel and efficient valve type arrester in which lining structure provides shatter prevention action and further serves to space the current discharge and arresting elements from the inner surface of the arrester housing.

A further object of the invention is to provide a novel

2

and efficient valve type arrester wherein an electrically insulative and heat resistant inorganic flexible or molded liner member is disposed between the inner surface of the arrester housing and the current discharge and arresting element or elements so as to provide shatter and explosion protection.

An additional object of the invention is to provide a novel and efficient valve type lightning arrester wherein a liner member is formed from asbestos paper and located for efficient prevention of shatter and explosion.

These and other objects of the invention will become more apparent upon consideration of the following detailed description along with the attached drawing, in which:

FIGURE 1 is an elevational view of a valve type lightning arrester constructed in accordance with the principles of the invention and having a portion thereof removed to provide a view of the arrester interior; and

FIG. 2 shows a perspective view of a liner member partly broken away and used in the arrester of FIG. 1.

More particularly, there is shown in FIG. 1 a lightning arrester 10 of a type to be described here to the extent necessary in developing an understanding of the invention. For a more particular description of structural and functional details which are not fully covered in this writing, reference is made to a copending application entitled Circuit Interrupter, Serial No. 181,687, filed by C. H. Carothers on March 22, 1962, now Patent No. 3,153,128, issued October 13, 1964 and assigned to the present assignee, and to another copending application entitled Terminal Connector, Serial No. 181,686, filed by R. J. Lawrence and C. H. Carothers on March 22, 1962 and also assigned to the present assignee.

Generally, the lightning arrester 10 is classified as a valve-type arrester and it comprises an elongated tubular housing or casing 12 in which there are disposed a spark gap assembly 14 and a non-linear resistance block assembly 16. In order to provide a discharge path for lightning current and to provide for arresting power following current, the assemblies 14 and 16 are connected in electrical series between line terminal 18 and ground terminal 20.

An insulative or porcelain cap 22 is supported in sealed relation to the upper end of the housing 10 and the cap 22 in turn provides support for the line terminal 18. Securance of the terminal 18 to the housing cap 22 can be provided by suitable means such as a threaded nut. 19. In order to connect the terminal 18 to a line conductor, an insulative hand wheel 24 is provided with a conductive insert member 26 slidably engageable with a threaded portion (not shown) of the terminal 18. A conductor can thus be secured to the terminal 18 between the insert member 26 and the terminal 18 as indicated by the reference character 28 simply by hand tightening movement of the hand wheel 24. A more complete description of this connector structure and the advantages thereof is set forth in the previously mentioned copending application, Serial No. 181,686 of R. J. Lawrence and C. H. Carothers.

The lower end of the arrester housing 10 is also closed in sealing relation, and in this instance the closure arrangement is provided in the form of a drop-out device 30. The drop-out device 30 supports the ground terminal 20 in a suitable manner and, further, in order to break the line to ground circuit and in this example to release internal pressure, is suitably arranged to become detached from the arrester housing 12 if an excessive heat producing fault current develops in the lightning arrester 10. Further description of the character of the drop-out device 30 or devices similar thereto can be obtained by reference to the aforementioned copending patent applications. An insulative hand wheel 32 similar or identical

to the hand wheel 24 is also provided for threaded engagement with the ground terminal 20. Securage of a ground conductor to the hand wheel 32 is accomplished in a manner similar to that described in connection with the line terminal 18.

The spark gap assembly 14 is disposed in this instance in a separate compartment 34 and is provided for the purpose of normally insulating the line terminal 18 and the line to which it is connected from ground. However, when a lightning surge appears at the line terminal 18, the spark gap assembly 14 undergoes electrical breakdown and a relatively low impedance arc discharge path is produced therethrough. The assembly 14 can thus include, in a manner similar to that described, for example, in the aforementioned application Serial No. 181,686, one or more spark gaps each of which comprises a pair of disc-shaped electrodes 36 spaced from each other by a centrally disposed insulative member or cylinder (not shown) which can be formed from rutile or other suitable insulative material. A hollow cylindrical arc barrier member 38 is disposed between each pair of electrodes 36 adjacent the outer periphery thereof.

An insulative elongated rod 40 is employed to hold the spark gap assembly 14 together. Thus, the electrodes 36, the previously noted central insulative spacers, and a contact plate 42 receive the insulative rod 40 through respective central openings therein. It is also to be noted that a partition member 44 can be employed to divide the spark gap assembly compartment 34 from compartment 46 in which the non-linear resistance block assembly 16 is disposed. The partition member 44 is formed from a resilient insulative material such as cork-neoprene and it also can receive the insulative rod 40 and otherwise be disposed against the contact plate 42 so as peripherally to engage the inner wall surface of the arrester housing 12.

Final securage of the spark gap assembly 14 in assembled form can be accomplished through attachment of respective U-shaped nuts 48 (only one shown) to each end of the insulative rod member 40. Outwardly projecting arm or arms 50 of each nut 48 provides circuit continuity, for example between the spark gap assembly 14 and the line terminal 18 or the securing nut 19 thereon.

The contact plate 42 is provided with a central projection (not shown) extending upwardly for engagement with the adjacent gap electrode 36 through the insulative partition member 44. Accordingly, good electrical contact between adjacent conductive members in the spark gap assembly 14, and tight resilient support for the entire assembly 14 is provided by means of conductive coil spring 52 which is preferably conductively shunted (not shown) and further is disposed between the contact plate 42 and upper contact plate 54 of the non-linear resistance block assembly 16 in the compartment 46.

One or more non-linear resistance blocks 55 are disposed between the upper contact plate 54 and a lower resilient coil spring 56 which makes electrical contact with the ground terminal 20 through the drop-out device 30. The block 55 is characterized with non-linearly decreasing resistance as a function of increasing voltage and for this reason the block 55 provides relatively low impedance to high voltage lightning discharges but relatively considerable impedance to lower voltage power follow currents. Accordingly, the block 55 is ordinarily effective to reduce the flow of power follow current after a lightning discharge has occurred through the arrester 10. The electrical properties just described can be provided for the block 55 through the selection of a suitable material, for example suitably processed silicon carbide or such processed silicon carbide with a binder such as a vitrified fired ceramic bond or sodium silicate.

However, the lightning arrester 10 can become damaged in use by unusually heavy lightning discharges or unusually heavy power current flows and such damage can initially take the form of the development of a fault in

the material of the resistance block 55. When a material fault does occur, the impedance characteristics of the block 55 are substantially altered or reduced and considerable current produced heat is generated so that resulting temperature rise produces vaporization of the block material. Build up of gas pressure and gas ionization in the arrester compartment(s) thus occurs. Similarly, it is also possible for excessive heat production and vaporization in the gap structure 14 to lead to such gaseous changes in the arrester compartment(s).

Under these conditions, undesired current arcing can occur, especially between the block 55 and the wall of the housing 12 or along the block 55 in the space between it and the wall of the housing 12. The described pressure build up or the thermal shock associated with the development of current arcing or a combination of these factors can accordingly cause the housing 12 to shatter or explode.

This can be true even if the drop-out device 30 is designed for ejection from the arrester housing 12 upon the development of a fault in the block 55. Thus, the development of shatter or explosion forces can occur in a shorter period of time than that which it takes the drop-out device 30 to respond to a developed fault. Furthermore, in numerous marketed lightning arresters, drop-out devices or drop-out arrangements are not effective to provide for pressure release from the arrester housing interior upon ejection thereof. It is also noteworthy that in some cases pressure build up in the interior of an arrester housing, such as after the development of a fault in the resistance block or blocks, is ineffective of itself to cause the arrester housing to shatter or explode but does cause such an explosion if the arrester housing is impacted by a serviceman's tool or the like. In such cases, there is considerable risk of personal injury to the serviceman.

In order to reduce or eliminate the risk of shatter or explosion under the described and other conditions, a tubular liner member 58 is disposed between the assembly 16 or the assembly 14 or both of these assemblies and the inner surface of the wall of the housing 12. In most applications, disposition of the liner member 58 between the block assembly 16 and the wall of the housing 12 will be sufficient substantially to prevent shatter or explosion of the housing 12.

The liner member 58 is preferably flexible or molded so that it can fit the contour of the block assembly 16 and further is so sized in thickness as preferably to provide good central positioning of the block assembly 16 relative to the inner surface of the wall of the housing 12. The material of the liner member 58 is preferably inorganic and non-carbonizing so as to be non-arc tracking, and it is also heat resistant as well as fireproof. In this manner, the liner member 58 is effective against current arc formation which is one of the apparent causes of the development of shattering or explosive forces. The material also provides some or preferably considerable gas absorption so as to inhibit pressure build up within the arrester housing 12.

Although fiberglass and other materials can be employed to form the liner member 58, it has been determined that asbestos paper has good qualifications on the basis of the above considerations. If a continuous roll of insulative material or asbestos paper is employed, the liner member 58 can be formed in several layers 60 (FIG. 2) or it can be formed as a single layer with a small amount of overlap if desired. The required thickness of the liner member 58 will of course to some extent depend upon the rating of the arrester in which it is employed.

In tests conducted for distribution type arresters, it was determined that, over a fault current range of 25 to 5000 amperes and under other controlled test conditions, the minimum thickness of asbestos paper that could be used to prevent explosion is .045 inch. In one series of the

tests, four wraps of asbestos paper having a thickness of .015 inch were employed and, in another series of tests, a single wrap of asbestos paper having a thickness of $\frac{1}{16}$ inch was employed. The asbestos paper can be made from either short or long asbestos fibers and preferably has a minimum fiber content of 88%. Fiberglass cloth having a thickness of $\frac{1}{16}$ inch also proved successful but advantages of using fiberglass in many applications are offset by manufacturing handling problems associated with it.

The foregoing description has been presented only to illustrate the principles of the invention. For example, it is clear that the invention has application in lightning arresters of considerably different structure from that shown for the arrester 10 of FIG. 1 so long as a basic need exists for preventing shatter or explosion of such arrester structures. Accordingly, it is desired that the invention be not limited by the embodiment described, but, rather, that it be accorded in interpretation consistent with the scope and spirit of its broad principles.

What is claimed is:

1. A lightning arrester comprising a generally cylindrical housing of insulating material, a plurality of arrester elements disposed in series relation in said housing and including a spark gap assembly and a non-linear resistance block assembly, said resistance block assembly including one or more blocks of molded material having a diameter less than the internal diameter of the housing, said arrester elements being centrally disposed in the housing with an annular space between the arrester elements and the housing, and a separate liner member disposed in said annular space and encircling at least a part of the arrester elements, said liner member comprising a non-adherent continuous member of heat-resistant inorganic material of sufficient porosity to absorb gas.

35

2. A lightning arrester comprising a generally cylindrical housing of insulating material, a plurality of arrester elements disposed in series relation in said housing and including a spark gap assembly and a non-linear resistance block assembly, said resistance block assembly including one or more blocks of molded material having a diameter less than the internal diameter of the housing, said arrester elements being centrally disposed in the housing with an annular space between the arrester elements and the housing, and a separate liner member disposed in said annular space encircling and substantially coextensive with the resistance block assembly, said liner member comprising a non-adherent continuous member of heat-resistant, non-tracking inorganic material of sufficient porosity to absorb gas.

3. A lightning arrester as defined in claim 1 in which the liner member is made of asbestos paper.
